US0D1032272S

(12) **United States Design Patent** (10) **Patent No.:** **US D1,032,272 S**
(45) **Date of Patent:** **** Jun. 25, 2024**

(54) **GRILL**

(71) Applicant: **Otto Wilde Grillers GmbH**,
Dusseldorf (DE)

(72) Inventor: **Christian Schrepfer**, Vienna (AT)

(73) Assignee: **OTTO WILDE GRILLERS GMBH**,
Dusseldorf (DE)

(**) Term: **15 Years**

(21) Appl. No.: **29/832,578**

(22) Filed: **Mar. 29, 2022**

Related U.S. Application Data

(62) Division of application No. 29/757,296, filed on Nov.
4, 2020, now Pat. No. Des. 947,590.

(57) **CLAIM**

The ornamental design for a grill, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front view of grill according to a first embodiment;

FIG. 2 is a left side elevation view thereof;

FIG. 3 is a rear elevation view thereof;

FIG. 4 is a right side elevation view thereof;

FIG. 5 is a top plan view thereof;

FIG. 6 is a perspective view thereof;

FIG. 7 is detail perspective view thereof;

FIG. 8 is a front view of grill according to a second embodiment;

FIG. 9 is a left side elevation view thereof;

FIG. 10 is a rear elevation view thereof;

FIG. 11 is a right side elevation view thereof;

FIG. 12 is a top plan view thereof;

FIG. 13 is a perspective view thereof; and,

FIG. 14 is detail perspective view thereof.
